(57) CLAIM

The ornamental design for a steam cleaner, as shown and described.

DESCRIPTION

FIG. 1 is a perspective view of a steam cleaner;
FIG. 2 is a front view thereof;
FIG. 3 is a rear view thereof;
FIG. 4 is a right side view thereof;
FIG. 5 is a left side view thereof;
FIG. 6 is a top view thereof;
FIG. 7 is a bottom view thereof.
FIG. 8 is a perspective view of a steam cleaner cradle;
FIG. 9 is a front view thereof;
FIG. 10 is a rear view thereof;
FIG. 11 is a right side view thereof;
FIG. 12 is a left side view thereof;
FIG. 13 is a top view thereof;
FIG. 14 is a bottom view thereof.
FIG. 15 is a perspective view of a hand-held steam cleaner;
FIG. 16 is a left side thereof;
FIG. 17 is a right side thereof;
FIG. 18 is a front view thereof;
FIG. 19 is a rear view thereof; and,
FIG. 20 is a top view thereof.

The steam cleaner cradle in FIGS. 8-14 and the hand-held steamer shown in FIGS. 15-21 are shown separate for clarity of illustration. The claim is directed to the entire assembly shown in FIGS. 1-7.

1 Claim, 20 Drawing Sheets
